UNITED STATES PATENT OFFICE.

OTIS A. MYGATT, OF NEW YORK, N. Y.

DESIGN FOR A REFLECTOR OR SIMILAR ARTICLE.

No. 38,558.

Specification for Design.

Patented May 14, 1907.

Application filed March 10, 1906. Serial No. 305,413. Term of patent 14 years.

To all whom it may concern:

Be it known that I, OTIS A. MYGATT, a citizen of the United States, residing at New York, in the county of New York and State of New York, have invented a new, original, and ornamental Design for a Reflector or a Similar Article, of which the following is a specification, reference being had therein to the accompanying drawing, forming part thereof.

The drawing is a plan view of a reflector embodying my design.

The body of the reflector is composed of one piece of glass. The top of the reflector is provided with reflecting prisms, grouped

about the central opening or collar to form a star. Between the points of the star the glass is left plain. The inside of the reflector shows the star in brilliant lines or facets.

I claim:

The ornamental design for a reflector or similar article having reflecting prisms arranged in form of a star as shown and described.

OTIS A. MYGATT.
